Primary Examiner — Elizabeth J Oswecki(74) *Attorney, Agent, or Firm* — Riverside Law LLP**CLAIM**

I claim the ornamental design for a santa stake, as shown and described.

DESCRIPTION

FIG. 1 is a perspective view of a santa stake showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is another perspective view thereof shown in a used condition with a plant shown in broken lines.

The broken lines depict environmental subject matter only and form no part of the claimed design.
